SPARK PLUG

George G. Burrell, Blairstown, and Leo Burrell,
Des Moines, Iowa

Application September 15, 1941, Serial No. 410,868

4 Claims. (Cl. 123—169)

The principal object of this invention is to provide a spark plug that is sealed against moisture, condensate and the like.

A further object of this invention is to provide a spark plug which may be built into the block of a motor, that will permit the changing of the points of the plug, and one that is sealed against moisture when in place.

A still further object of this invention is to provide a high tension shield for spark plugs, distributors, or the like that is water-proof, that statically shields the points, and that is provided with a means for shielding the complete ignition system against static discharge or radio interference.

A still further object of this invention is to provide a spark plug that is extremely economical in manufacture, durable and efficient in use.

These and other objects will be apparent to those skilled in the art.

My invention consists in the construction, arrangement and combination of the various parts of the device, whereby the objects contemplated are attained as hereinafter more fully set forth, pointed out in our claims, and illustrated in the accompanying drawing, in which:

Fig. 1 is a side cross sectional view of our plug ready for use.

Fig. 2 is a side elevational view of the spark plug more fully illustrating its structure.

Fig. 3 is a side elevational view of the removable point carrier and insulating sleeve shown in Fig. 1.

Fig. 4 is a bottom elevational view of the plug.

Fig. 5 is an enlarged cross sectional view of the upper portion of the plug shield showing the insulating cap and stylus contact point.

Fig. 6 is an enlarged sectional view of a portion of a motor block illustrating the method of placing the points in a motor head without the use of a base on the plug.

Spark plugs have followed the same general line for many years. They have exposed porcelain insulators, are not statically shielded, are not water-proof, and do not permit the changing of the points. Furthermore, they are subject to breakage and have exposed contact wires and connections. These plugs are very fragile and due to changes of operating temperature, the porcelains crack and become short-circuited. We have overcome such disadvantages as will be appreciated and as will be hereinafter more fully set forth.

Referring to the drawing, we have used the numeral 10 to indicate a base portion of the

usual type and having the threaded sleeve member 11 thereon so that it may be screwed into a motor block or head. The inside base chamber of the base 10 is tapered and the upper inside portion is threaded to receive an elongated sleeve member or shield 12. This shield portion can be threaded into the base member 10 and has its inside hollow. I have used the numeral 13 to indicate a porcelain insulator having therein a central electrode 14 and an enlarged tapered portion 15 as shown in Fig. 1. The upper portion of the insulator extends upwardly to form a sleeve 16, leaving a shoulder 17 between this upright portion 16 and the enlarged portion 15. The numeral 18 indicates a band crimped and secured about the enlarged tapered portion 15 and having thereon an electrode 19 which extends downwardly and thence is curved around the center electrode 14 adjacent the base of the plug 10 as shown in Fig. 4. It will be noted, by referring to Fig. 4, that the curled portion of the ground electrode 19 extends in a circle having a constantly decreasing gap between the central electrode 14 and the ground electrode 19. This provides a self-adjusting point giving the plug a much longer life and much more sparking surface. The insulator 13 is placed within the base member 10 and the sleeve 12 is then threaded into the top of the base 10, forcing the band 18 into contact with the base member 10 in the manner shown in Fig. 1. The shoulder 17 is filled with a sealing compound and the tightening action of the sleeve 12 enforcing the tapered sleeve 18 into the tapered receptacle of the base 10 provides sufficient seal to prevent compression, leaks, and to make a positive ground for the electrode 19. The numeral 20 indicates a stylus on the upper end of the insulator sleeve 16 which is in electrical communication with the electrode 14 as shown in the drawing. We have used the numeral 21 to designate an insulative cap having the tapered inside chamber 22 and capable of being threaded into the upper end of the sleeve 12. The numeral 23 indicates an ordinary high tension wire over which the sleeve 21 is placed, and which has its end portion forced onto the stylus 20 to establish contact with the center wire after which the cap 21 is threaded into place, thereby forcing the wire down on and into contact with the stylus 20, at the same time providing an inherent seal between the cap portion 21 and the wire 23. If the wire 23 is of the shielded type, the shield 24 is connected by spring clips or the like 25 to a rim or bead 26 formed about the upper end of the sleeve 12. When the plug as shown in Fig. 1

is placed in a motor block, the whole exterior unit of the plug is shielded from moisture, dirt, oil, air and the like, and is also statically shielded to prevent radio interference. Referring to Fig. 6 of the drawing it will be noted that the base as represented by the base 10, can be formed in the head of the motor. A head so formed has been illustrated in Fig. 6 and designated by the numeral 27. The points are then dropped into the opening so that the sleeve 18 is in contact with the side walls of the head and the sleeve or shield 12 is then screwed into the block. This permits the water jacket to be brought adjacent the plug or motor points for keeping the plug cool and eliminates the forming of a large depression in an ordinary motor head for the accommodation of the spark plug. This structure increases the cooling surface within the heads and provides a cooler plug, as well as simplifying the structure of the motor block head.

The practical operation of our device is as follows:

The base member 10 is threaded into the spark plug opening of a motor. The electrode carrier comprising the insulator 13 with its attendant sleeve 16 and enlarged portion 15, sleeves 18, electrodes 14 and 19, and stylus 20 is then dropped into the base portion. The cover member or shield 12 is then screwed into the upper end of the base 10 and forced tightly down upon the shoulders 17, forcing the cone formed by the sleeve 18 into the cone formed within the base 10 and providing a tight fit. The cap 21 is then placed over the end of the ignition wire, and the end of the wire forced down onto the stylus 20. The cap 21 is then threaded into the upper end of the shield 12 and by virtue of the tapered inside bore 22, forces the wire tightly against the stylus 20, and at the same time effectively seals the upper end, in conjunction with the wire 23, to form a water-proof unit. The shield 24 of the wire 23 is then clipped by means of the fingers 25 to the bead 26, and the device is ready for use.

This whole unit above the motor head may be immersed in water and will still function properly. There are no exposed terminals or connections, and the porcelain is not subjected to the cooling drafts to permit it to crack from expansion and contraction. The same set of points may be dropped into the motor block 27, and the threaded cap or cover 12 placed therein in the manner shown in Fig. 6, permitting the water cooling of the head directly adjacent the spark plug. Referring to Fig. 5, this connection may be used on distributor caps and other high tension devices for providing a water-proof shielded contact point, leaving no exposed terminals and preventing the condensation of moisture about the insulated portion of the device to which it is attached.

All of the electrodes are carried on one member, that is, the member shown in Fig. 3, and therefore, the construction shown in Fig. 6 is possible. By using the curved electrode 19, greater firing surface is obtained, permitting it to progressively burn off and still retain a gap within the tolerance required by the electrodes or contact points 14 and 19. With our device, it is possible to have the upper member exposed to the direct blow or draft of the fan for cooling the plug without danger of cracking the porcelain insulator. There is no danger of accidentally touching an exposed contact point or breaking the plug by an inadvertent slip of a wrench or like. The whole plug is shielded electrically and

atmospherically, permitting the use of a cold type plug in all types of motors and the easy replacement of the point portions of the plug without it being necessary to purchase a new

base portion or cover member and is of prime importance. The upper portion can be used for a water-proof ignition system by using the structure shown in Fig. 5 in conjunction with magneto's, distributors and the like. Our device fulfills all of our objects and presents many more obvious advantages. The porcelain portion of the device will hereinafter be called an insulator, and the shield 12 will be called a shield member or cover.

15 Some changes may be made in the construction and arrangement of our improved spark plug without departing from the real spirit and purpose of our invention, and it is our intention to cover by our claims any modified forms of structure or use of mechanical equivalents, which may be reasonably included within their scope.

We claim:

1. In a device of the class described, a base member, an insulator, a metallic sleeve on said insulator capable of contacting said base member, an electrode on said sleeve, a second electrode extending through said insulator and resting adjacent said first mentioned electrode, a shoulder on said insulator, a shield member capable of being threaded into the top of said base member and holding said insulator and said sleeve in position, a stylus contact point on the upper end of said insulator in communication with said second mentioned electrode, an insulated wire capable of being adjusted on said stylus and in electrical communication therewith, a cap member threaded into the upper end of said shield member and forcing said wire on said stylus and sealing the upper end of said shield to provide a moisture-proof cap, shielding on said wire, and a clip member in communication with said shielding capable of establishing electrical contact with said shield portion.

2. In a spark plug, a base portion, an insulating sleeve in said base portion, a shoulder on said sleeve, two electrodes on said sleeve, a shield portion capable of being threaded into said base portion and against said shoulder of said sleeve; said shield extending around and beyond said sleeve portion, and an insulating cap member threaded into the upper end of said shield and capable of holding a wire; said insulating cap, said wire, said shield and said base forming a water-tight enclosure for said insulating sleeve.

3. In a device of the class described, a hollow base portion, an insulated portion having an electrode extending therethrough longitudinally, a second electrode secured to the outside of said insulated member and capable of contacting the inside portion of said base member when placed therein, a cover member threaded into said base member and holding and enclosing said insulated member and said electrodes therein, a contact point on the upper end of said first mentioned electrode capable of being forced into electrical communication with an electric lead wire, and a cap portion having its inside walls tapered and having its outside portion threaded so as to be received by said cover member for holding said wire and sealing said cover member.

4. In a device of the class described, a base member, an insulator, a metallic sleeve on said insulator capable of contacting said base member, an electrode on said sleeve, a second electrode

extending through said insulator and resting adjacent said first mentioned electrode, a shoulder on said insulator, a shield member capable of being threaded into the top of said base member and holding said insulator and said sleeve in position, an insulated wire capable of being adjusted on said second mentioned electrode and in

5 electrical communication therewith, and a cap member threaded into the upper end of said shield member for sealing the upper end of said shield to provide a moisture-proof cap.
